UNITED STATES PATENT OFFICE.

EDUARD PIELOCK, OF BERLIN, GERMANY.

HEATING-TUBE FOR TUBULAR STEAM-BOILERS.

948,741.

Specification of Letters Patent.

Patented Feb. 8, 1910.

Application filed July 13, 1908. Serial No. 443,307.

To all whom it may concern:

Be it known that I, EDUARD PIELOCK, a subject of the German Emperor, and resident of Berlin, Germany, have invented certain new and useful Improvements in Heating-Tubes for Tubular Steam-Boilers, of which the following is a specification.

This invention relates to improvements in heating tubes for tubular steam boilers, which generally have a maximum diameter of 4 inches and its object is to insert therein open rings, which may be also made in spiral form, or the rings inserted are closed and arranged eccentric, said rings being designed to perform the functions of a baffle and so disposed that they do not form any impediment to the cleaning of the tubes.

The open or the eccentric closed rings offer the advantage that on the one hand the gases which are imperfectly oxidized are by their being intimately mixed again brought to a higher oxidation-degree whereby the combustion of the same becomes more perfect, a sufficient air supply being of course essential therefor, while on the other hand the slack collected in the smoke-chamber is much finer than with heating tubes without rings, the rings acting in this case as spark catchers so that the larger coal particles which are led through the tube by the intense air draft are on the rings dashed to pieces and escape as such through the flue in red-hot condition. A further advantage of the rings consists in that by inserting the same into a part of the heating tubes a more uniform distribution of the heating gases on all tubes is obtained. As known, the gases take the shortest way to the flue so that mostly,—depending on the vacuum in the smoke-chamber or on the draft of the flue,—the gases escape through the lower and lateral heating tubes, which especially in locomotives can be seen from the larger deposition of ashes therein. By the non-uniform

passage of the gases through the tubes the latter are of course also strained in a non-uniform way, but when rings are inserted in the highest strained tubes the resistance in these tubes is somewhat increased for the gas passage and therefore a larger gas quantity is led through the less strained tubes without rings.

The accompanying drawing shows the subject matter of the invention.

Figures 1 and 2 are cross sections through a heating tube with different forms of open ring, while Fig. 3 is a longitudinal section through the same; Figs. 4 and 5 show in cross and longitudinal section respectively a heating tube provided with an open spiral ring; and Figs. 6 and 7 are a longitudinal and cross section respectively through a heating tube provided with a closed eccentric ring.

The rings are preferably placed in the heating tube at certain intervals other in such a manner that the gaps of two successive rings lie diametrically opposite to each other.

Having fully described my invention, what I claim and desire to secure by Letters Patent is:

1. In a heating tube for tubular steam boilers, a plurality of rings mounted at intervals therein to perform the functions of a baffle and so disposed as to form no impediment to the cleaning of said tube.

2. In a heating tube for tubular steam boilers, eccentric rings mounted at intervals therein and designed to perform the functions of a baffle.

In testimony whereof I have hereunto set my hand in the presence of two subscribing witnesses.

EDUARD PIELOCK.
